UNITED STATES PATENT OFFICE.

BYEON E. ELDRED, OF NEW YORK, N. Y.

METHOD OF UTILIZING AIR WAVES FOR AURAL KINESITHERAPY.

No Drawing.

Application filed July 7, 1927. Serial No. 204,148.

This invention relates to a method for utilizing air waves for aural kinesitherapy. The method consists in producing and emitting into the surrounding space a continuous and sustained succession of rhythmical air waves of suitable pitch and amplitude but preferably of not pronounced tonal quality for the human ear whereby the ears of persons of difficult hearing within the influences of these waves are rendered more sensitive to normal sounds.

My method is useful not only (1) in enabling more or less deaf persons to hear sounds or speech of normal intensity while they are within the influence of such waves, but (2) also for improving the audition of some classes of deaf persons by repeated subjection to the influence of such sensitizing waves.

It is to this latter form of the invention that the present application relates, the first form being claimed in my earlier application Serial No. 755,077, filed Dec. 10, 1924, of which this present application is a continuation in part.

In practicing the form of the invention now claimed, I do not wish to limit myself to the use of inaudible frequencies in the carrying out of my invention, as certain audible frequencies, especially those approaching the limits of audibility, will be found to be quite satisfactory. The adjustment of amplitude is more important than the adjustment of frequency.

It is, however, desirable to use a wave which has little or no tonal quality for the human ear, because such a wave effects no auditory nerve response, and for that reason may be applied with the desired strength or amplitude without causing nerve fatigue.

When I use an audible frequency wave, I designedly employ one which is audible with difficulty, because a wave which furnishes vibrations causing auditory nerve response and when sustained for the period of several minutes may cause auditory nerve fatigue and ear discomfort. This is absent in the soundless vibration or one that is comparatively devoid of tonal quality. Frequencies well outside the normal useful range, or approaching the limits, may be employed with high amplitude without fatigue. Vibrations of the lower range of frequencies are less irritating and penetrating than those of higher range.

According to the present invention I have

found that it is important that the rhythmical sensitizing wave shall be of substantially simple harmonic character, or one which is as free as possible from other waves of different frequency compounded therewith. For the purposes of the present case, I term waves having the characteristics above described, "harmonious waves".

The mechanical effect of such a continued rhythmical air wave on the ear-drum is a succession of pressure increments and decrements. Obviously, waves other than of purely sinusoidal form will produce the same general effect of applying force to the ear-drum by a continued series of gradual increments and decrements.

According to this invention, therefore, the harmonious sensitizing wave is kept as free as possible from compounded staccato or disturbing waves. When persons of difficult hearing are subjected to this purer form of wave of sufficient amplitude, for one or more periods of time, their ability to hear under ordinary conditions may be improved and often persists for hours or even days.

To produce this effect, the waves must be of sufficient amplitude or force producing effect to have the desired effect on the mechanism of the ear, and the amplitude of such waves can easily be determined by experiment and can readily be controlled either by regulating the apparatus which produces the wave, or by locating the deaf person at varying distances from such source of waves.

It is not essential that the waves should be of such high or low frequency as to be substantially inaudible, although for the reasons above stated they preferably approach the limit of sound capable of producing auditory nerve response.

I believe that I am the first to produce this effect and the first to suggest or provide the means by which this effect may be produced.

Any suitable apparatus for producing a substantially pure wave of the kind above referred to may be used.

My method operates to effect the passive manipulation of the mobile parts of the ear to a regulable and controllable degree, which is predetermined by the amplitude of the vibration of the harmonious sensitizing wave. In the practice of my invention I have found that the amplitude of the waves required is much greater than the amplitude of the waves which would produce ordinary sounds.

loud enough to be heard without discomfort. In other words if waves well within the normal audible range were emitted with amplitudes such as I use, the result would be an ear distressing noise. As the excursion of the mobile parts of the ear is a direct function of the application of the force of the vibration imparted to the drum skin it will be evident that my method provides means 5 for bringing about abnormal excursion without corresponding auditory nerve stimulus, which would otherwise be not only distressing but dangerous: for example, this 10 condition of abnormally strong air wave vibrations of audible frequency brings about what is commonly known as boiler maker's deafness among the workers in boiler shops.

I may employ a major vibration which in 15 itself supplies the desired force with corresponding reaction to bring about the desired result, having combined therewith a vibration of distinct tonal quality but of low amplitude. The combined vibrations effect 20 auditory nerve stimulus to a degree equal to or even less than could the low amplitude vibration if present alone and not combined 25 with a major vibration. The combination of such a distinctly minor vibration with the

major vibration in no way defeats the purpose and effect of the major vibration, as I 30 employ it.

The combining of a distinctly minor amplitude vibration of a different frequency with a sinusoidal vibration of different frequency and far greater amplitude produces a 35 wave which, strictly speaking, might not be termed a sinusoidal wave but none the less it produces the effect of a sinusoidal wave to all the intents and purposes of this invention, and provides the effect of applying 40 force to the ear drum in a continued series of gradual increments and decrements.

I claim:

A method of utilizing air waves for aural kinesitherapy which consists in emitting into 45 surrounding space a continuous and sustained succession of air waves characterized by their harmonious wave form and of such force producing characteristics as to cause pressure variations greater than those occurring in ordinary sounds, said waves having a frequency adjacent the marginal frequency of the audible range.

In testimony whereof, I affix my signature.
